(57) **CLAIM**

The ornamental design for a partition screen with a transparent display, as shown and described.

DESCRIPTION

1. Partition screen with a transparent display

1.1 : Perspective

1.2 : Front

1.3 : Back

1.4 : Left

1.5 : Right

1.6 : Top

1.7 : Bottom

1.8 : Exploded

1.9 : Exploded

The present design is a partition screen in which a transparent display is disposed; an upper area of the partition to which the transparent display is coupled and a lower area of the partition in which a drive unit is embedded, may be disposed stably in a ratio of 1:1, and the drive unit and the cable may be embedded, thereby realizing a clean exterior; fig. 1.8 is an exploded perspective view of the glass portion, the transparent display and the partition body of the present design; writing is possible on the glass portion to be used like an electronic bulletin board; fig. 1.9 is an exploded perspective view of the cover separated from the lower end.
